SPRAY PROJECTOR FOR AUTOMATIC DISH
WASHING AND DRYING MACHINERobert Burkle, North Bergen, N. J., assignor of
one-half to Richard Merrifield, New York,
N. Y.

Application March 17, 1933, Serial No. 661,245

3 Claims. (Cl. 299—67)

This invention relates to new and useful improvements in a spray projector for automatic dish washing and drying machines.

This application is a continuation in part of my application entitled Automatic dish washing and drying machine, Serial No. 615,287, filed in United States Patent Office on June 4, 1932.

The invention has for an object the construction of a spray projector with perforations staggered between sprayer arms which is adapted to efficiently spray the hot water, the cold water and the necessary grease solvent and other liquids upon the dishes.

Still further the invention contemplates an arrangement whereby spray arms are fixed upon a hollow member rotatively mounted and an arrangement whereby the flow of the liquid causes rotation of the member so that the spray arms rotate and thoroughly spray the dishes.

Still further the invention contemplates an arrangement whereby the spray projector may be located above or below the basket containing the dishes and so direct the spray against all portions of the dishes.

Still further the invention contemplates the provision of a novel arrangement of blades within the spray projector adapted to cause the liquid to move in a certain manner and cooperate with other blades to cause the rotation of the member carrying the spray arms.

As another object of this invention it is proposed to provide a plurality of perforations in the rotative member so that the liquid may also discharge from the central area of the spray projector.

As another object of this invention, it is proposed to provide an arrangement whereby the perforations upon the spray arms are automatically closed upon the cutting off of the supply of liquid so that dripping is eliminated.

Furthermore an arrangement is proposed whereby the perforations within the rotative member are also simultaneously closed with the closing of the perforations upon the spray arms.

Attention is called to the fact that even though the supply of liquid is cut off, liquid remains within the spray projector and unless some arrangement is made to prevent the dripping this liquid will slowly drip out and wet the dishes which are being dried. It is for this reason that the provision of the automatic cut off against dripping is provided.

Still further this invention has in mind the provision of sleeves with closed ends slidably mounted upon the spray tubes and provided with

perforations adapted to align in a certain position of the sleeves with the perforations in the spray tubes and an arrangement whereby the position of the sleeves is controlled to effect the passage of liquid or to arrest the passage of liquid.

Still further the invention contemplates the provision of cut off slides arranged upon the rotative member and formed with perforations adapted in one position to align with the perforations of the member and an arrangement whereby each of said slides is automatically moved so as to either allow the passage of liquid or cut off the supply.

As another object of this invention it is proposed to construct a spray projector as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a side elevational view of a spray projector constructed according to this invention.

Fig. 2 is a fragmentary enlarged bottom view of the central portion of Fig. 1.

Fig. 3 is a fragmentary enlarged longitudinal section view of Fig. 1.

The spray projector according to this invention comprises a bracket 10 which is provided with a central opening 11 for supply liquid. The opening 11 is formed with threads so that a supply line 12 may be threadedly engaged therewith and support the bracket in addition to supplying the liquid. A hollow member 13 is rotatively mounted upon the bracket 10 and is adapted to receive the liquid and is formed with diametrical- 35
ly opposite discharges 14 for the liquid. The rotative mounting of the hollow member 13 is accomplished by the provision of a ring 15 arranged on the bracket 10. The bracket 10 is provided with a top flange 16 and a cylindrical bottom portion 17. The ring 15 is arranged within a peripheral groove formed upon the bottom portion 17. The ring itself projects from the surface of the cylindrical portion 17. The hollow member 13 is formed at the top with a cylindrical 40
portion 18 in which a bushing 19 is threadedly engaged. This bushing acts between the flange 16 and the ring 15 to accomplish the rotative mounting of the hollow member.

A plurality of baffle blades 20 are arranged 55

within the central opening 11 and are adapted to cause the passing liquid to assume a turning or rotative motion and to impinge against a plurality of other blades 21 fixed upon and within 5 in the hollow member 13 and adapted to cause rotating of the hollow member. After the liquid impinges against the blades 21 it discharges through the discharge openings 14. Spray tubes 22 threadedly engage and project radially from 10 the discharges 14. These spray tubes are provided along one of their sides with a plurality of perforations 23. If the spray projector is for use above the basket of dishes in the washing machine then the perforations 23 are located 15 along the bottom sides of the spray tubes. The particular spray projector is intended also for location below the dish containing basket of the washing machine in the inverted position.

A means is provided for automatically cutting 20 off the passage of the liquid through the openings 23 so as to prevent dripping when the liquid supply is cut off. This means comprises sleeves 24 slidably engaged upon the tubes 22 and formed with closed ends 25 so as to cause an urge which 25 will tend to move the tubes outwards when there is liquid pressure within the spray projector. The sleeves 24 are longitudinally slidable upon the tubes within limits as determined by pins 26 projecting from the tubes 22 and engaging in small 30 longitudinal slots 27 formed in the sleeves 24.

The sleeves 24 are provided with perforations 28 adapted in one position of the sleeves to align with the perforations 23 in the spray tubes and in another position to be out of alignment. More 35 particularly it is necessary that the perforations 28 be out of alignment with the perforations 23 when the sleeves 24 are in the retracted positions. A resilient means is provided for normally urging the sleeves 24 into the retracted positions and comprises springs 29 arranged coaxially upon the spray tubes 22 and the sleeves 24 immediately at the bases of the spray tubes. These springs have one of their ends 30 attached upon the spray tubes 22 and other of their ends 40 45 30' attached upon the sleeves 24 and so provide the necessary urge to move the sleeves 24 into the retracted positions. These springs 29 are of such strength as to give under the pressure of the flowing liquid within the spray projector so that the sleeves 24 may move automatically to the extended positions as allowed by the slots 27. In these extended positions the perforations 50 55 28 are in line with the perforations 23 and so allow the passage of the liquid through the perforations.

The hollow member 13 is also provided with a plurality of liquid passage openings 31 arranged at the bottom of the hollow member and adapted to direct the liquid downwards at the 60 center of the spray projector. An arrangement is also provided for preventing dripping through these perforations. This arrangement comprises a pair of slides 32 slidably mounted upon the bottom of the hollow member 13 and formed with 65 perforations 33 adapted to align with the perforations 31 in spread positions of the slides 32. The slide mounting of the slides is accomplished by headed studs 34 mounted upon the bottom of the hollow member 13 and projected 70 through longitudinal slots 35 formed upon the slides 32. Several arms 36 connect one of the slides 32 with the sleeve 24 nearest it and other similar arms 36 connect the other slide 32 with the other sleeve 24. The normal positions of the 75 slides 32 is illustrated in Fig. 3 of the drawing

in which the perforations 31 are cut off. Simultaneously with the motion of the sleeves 24 to their extended positions the slides will be correspondingly moved and the perforations 33 aligned with the perforations 31 simultaneous 5 with the alignment of the perforations 28 with the perforations 23.

A flexible fin 37 of rubber, metal, or any other suitable substance is shown mounted upon each of the outer ends of the sleeves 24. These fins are 10 intended to coact with a trip stop arranged upon the dish washing and drying machine so as to stop rotation of the spray projector when the liquid supply is cut off. It will readily be understood that due to momentum the spray projector 15 will tend to rotate and this motion will cause the tendency of dripping to be amplified. Consequently, it is paramount that rotation of the spray projector be arrested at the earliest moment after the liquid supply is cut off. The 20 details of the automatic tripping is illustrated and described in the application mentioned at the beginning of this specification.

While I have shown and described the preferred embodiment of my invention, it is to be 25 understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A spray projector for dish washing and drying machines, comprising a bracket with a central opening for the supply of liquid under pressure, a hollow member rotative on said bracket to receive said liquid and having diametrically opposite discharges for the liquid, means for causing rotating of said hollow member upon the passage of said liquid, spray tubes in and projecting from said discharges and having perforations on the sides for the discharge of the liquid and also having opened outer ends, and sleeves with closed ends longitudinally slidably mounted upon said spray tubes and having perforations adapted while said sleeves are in extreme radial positions to align with the perforations in said spray tubes and in other positions of said sleeves to be out of alignment, means for limiting the sliding of said sleeves upon said tubes, and resilient means for urging said sleeves into the latter positions, said means for limiting sliding of the sleeves comprising pins projecting from said spray tubes and engaging in short longitudinal slots formed in said sleeves.

2. A spray projector for dish washing and drying machines, comprising a bracket with a central opening for the supply of liquid under pressure, a hollow member rotative on said bracket to receive said liquid and having diametrically opposite discharges for the liquid, means for causing said hollow member to rotate upon the passage of said liquid, spray tubes in and projecting from said discharges and having perforations for the discharge of the liquid, and sleeves with closed ends longitudinally slidably mounted upon said spray tubes and having perforations adapted while said sleeves are in extreme radial positions to align with the perforations in said spray tubes and in other positions of said sleeves to be out of alignment, means for limiting the sliding of said sleeves upon said tubes, and resilient means for urging said sleeves

into the latter positions, comprising springs arranged upon the inner ends of said spray tubes and each spring having one of its ends connected upon the spray tube and the other of its ends attached upon said sleeve.

3. A spray projector, comprising a bracket with a central opening for the supply of liquid under pressure, a hollow member rotative on said bracket to receive said liquid and having diametrically opposite discharges for the liquid, means for causing rotation of said hollow member upon the passage of said liquid, spray tubes in and projecting from said discharges and having perforations, for the discharge of the liquid, and sleeves with closed ends longitudinally slidably mounted upon said spray tubes and having perforations adapted while said sleeves are in extreme radial positions to align with the perfo-

rations in said spray tubes and in other positions of said sleeves to be out of alignment, means for limiting the sliding of said sleeves upon said tubes, and resilient means for urging said sleeves into the latter positions, said bracket being formed with perforations so that the liquid may also discharge at the center of said spray projector, slides mounted upon said bracket and having perforations adapted to align with the perforations on said bracket in extended positions, and arms connecting said slides with said sleeves so that the perforations of the slides and bracket align when the perforations of said sleeves and spray tubes align and the perforations of said slides and bracket are out of alignment when the perforations of said sleeves and spray tubes are out of alignment.

ROBERT BURKLE.
